Paterson(57) **CLAIM**

The ornamental design for a toy, as shown and described herein.

DESCRIPTION

FIG. 1 is a front, right side, top perspective view according to my design for toy.

FIG. 2 is a front view of the toy shown in FIG. 1.

FIG. 3 is a rear view of the toy shown in FIG. 1.

FIG. 4 is a left side view of the toy shown in FIG. 1.

FIG. 5 is a right side view of the toy shown in FIG. 1.

FIG. 6 is a top view of the toy shown in FIG. 1; and, FIG. 7 is a bottom view of the toy shown in FIG. 1. Broken lines are used to illustrate portions of the toy that form no part of the claimed design.
